CLAIM

The ornamental design for the wall rack for hanging sheets or the like, as shown and described.

DESCRIPTION

FIG. 1 is a perspective view of a wall rack for hanging sheets or the like showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a side elevational view thereof taken from the left of FIG. 1, the other side elevational view being a mirror image of FIG. 6; and

FIG. 7 is a bottom perspective view of the central hanger shown separately for clarity of illustration.

FIG. 1

FIG. 2

FIG. 3

FIG. 5

FIG. 7
